Primary Examiner — Derrick Holland*Assistant Examiner* — Jennifer O King(74) *Attorney, Agent, or Firm* — Evan Law Group LLC**(57) CLAIM**

The ornamental design for a flexible fuel generator, as shown and described.

DESCRIPTION

FIG. 1 is a front perspective view of a flexible fuel generator;
 FIG. 2 is a back perspective view thereof;
 FIG. 3 is a left side perspective view thereof;
 FIG. 4 is a right side perspective view thereof;
 FIG. 5 is a top perspective view thereof;
 FIG. 6 is a bottom perspective view thereof;
 FIG. 7 is a front, top, and left side perspective view thereof;
 and,
 FIG. 8 is a back, top, and left side perspective view thereof.
 The broken lines shown represent unclaimed subject matter and form no part of the claimed design.

1 Claim, 8 Drawing Sheets# US D733,052 S
